KNOCKDOWN FURNITURE

George W. Anderson, Port Washington, N. Y.

Application February 16, 1949, Serial No. 76,702

3 Claims. (Cl. 155—196)

1

This invention relates to knock-down furniture and more particularly to a chair made principally of pieces of plywood or like material.

Among the objects of the invention is to provide a knock-down chair or like article of furniture comprising a minimum of separable pieces which may be easily erected to form a chair and disassembled into flat pieces for carrying and storage purposes.

Another object of the invention is to provide a chair having a resilient supporting structure bowed to shape and restrained from returning to its normal state by a seat member and a stretcher which together cooperate with the supporting structure and hold the assembly as a rigid unit.

While the outline of the various pieces of a chair may vary for producing chairs having different appearances and uses, a chair constructed in accordance with the principles of this invention includes a sheet of resilient material such as plywood which is adapted to be bowed to form a rear and forwardly extending supporting structure, and seat and stretcher members formed to fit within the bowed supporting structure and to cooperate with the inner surfaces of the bowed supporting structure for maintaining its form and also having means cooperating with the side portions of the bowed supporting structure to restrain the normal tendency thereof to return to a flat condition. The forward portion of the stretcher is pivotally mounted with respect to the sides of the supporting structure, and the side portions of the stretcher are so shaped with respect to the inner surface of the supporting structure as to limit the pivotal movement of the stretcher when mounted in place. The forward portion of the seat member is also pivotally connected to the sides of the supporting structure and it is so formed as to provide a locking fit with the interior of the bowed supporting structure when the seat member is in place over the stretcher.

The means by which the seat member and stretcher are pivotally mounted to the supporting structure engage openings in the sides of the supporting structure and have fastening elements which are manipulatable to separate the seat member and stretcher from the supporting structure by a simple pivotal movement.

The novel features which are characteristic of this invention will be better understood by referring to the following description taken in connection with the accompanying drawing in which a specific embodiment thereof has been set forth for purposes of illustration.

2

In the drawings:

Fig. 1 is a perspective view of a chair embodying the principle of the invention;

Fig. 2 is a vertical section on line 2—2 of Fig. 1;

Fig. 3 is a view of the chair as seen from above with parts broken away;

Fig. 4 is a development of the supporting structure of the chair;

Fig. 5 is a plan of the stretcher; and

Fig. 6 is a plan of the seat member.

The chair illustrated in the drawings is designed for use by a child, but it may be built on a larger scale and embody features of design more suitable for adult use. The chair includes a supporting structure 10, a stretcher 11 and a seat member 12, which when assembled together as illustrated in Fig. 1, constitutes a complete chair. The construction is particularly suitable for manufacture from plywood or from other materials having similar characteristics. Each of the main pieces may be stamped or die-cut from sheet material, once their relative proportions and design have been determined. As illustrated in Fig. 4, the supporting structure is so shaped as to provide a straight lower edge 13 which is adapted to rest upon the floor and support the back 14 and side portions 15 and 16 perpendicular to the floor, but, if desired, the lower edge 13 may be curved to incline the supporting structure with respect to the floor or to give a desired decorative leg structure. The upper edge 17 of the back portion 14 is formed to merge with the edges of the side portions 15 and 16 of lower height and provide arm rests 18 and 19. An opening 20 for handling the chair and openings 21, 22, 23 and 24 may be cut from the blank material at the time the supporting structure is cut. The openings 21 and 22 serve to support studs extending from the stretcher 11, and the openings 23 and 24 serve to support studs extending from the seat member 12, when the chair is assembled.

As will be more clearly understood in the following description the depth of the flat areas of the side portions 15 and 16 may be of any desired dimension, it being necessary only that length of supporting structure 10 between side edges be no greater with respect to the depth of the stretcher 11 than will permit the stretcher to intersect the curved portions of the back 14 and of the side portions 15 and 16 when the stretcher is mounted in position of use.

The stretcher 11 and the seat member 12 may also be made of sheet material, such as plywood, and are so shaped as to fit within and engage the inner surface of the supporting structure 10 when

the latter is bowed to form the chair, as illustrated in Fig. 1. The contour of the stretcher 11 includes a front edge 25 and a rear edge 26 which are parallel to each other, and side edges 27 and 28 which are curved towards the rear to form traces of the intersection of the plane of the stretcher with the curve of the back 14 and of the side portions 15 and 16, respectively, of the supporting structure 10 when the chair is assembled and the rear edge 26 of the stretcher underlies the under surface of the seat 12.

The stretcher is pivotally supported adjacent its forward edge by studs 29 and 30 extending from opposite side edges 27 and 28, respectively, of the stretcher. Each of the studs may be constituted of an inner core projecting from the material of the stretcher, and this inner core preferably has attached to its surfaces members 31 and 32 to provide a cylindrical bearing. These members 31 and 32 may be glued or otherwise fastened to the core, and the member 32 may extend across the stretcher to form a portion of the stud at its other edge, as illustrated in the drawings. The studs may be otherwise provided as in the form of metallic clips fastened to the stretcher. The cores of the studs are formed when the stretcher is stamped or die-cut from blank material and the wings 33 and 34 are preferably formed in the same operation. The holes 21 and 22 in the supporting structure 10 are shaped to provide curved bearing surfaces for the studs and slots to allow for the passage of the wings 33 and 34 therethrough.

When the chair is to be assembled, the sheet constituting the supporting structure 10 is bowed by bringing the side portions 15 and 16 towards each other until the studs 29 and 30 are engaged in the openings 21 and 22. The stretcher is then rotated on the axis of the studs to the position illustrated in Figs. 1 and 2. Once the stretcher is rotated, the stretcher acts as a tension member as the wings of the studs 29 and 30 restrain the natural tendency of the sheet 10 to unfurl. Since the side edges 27 and 28 of the stretcher are so shaped as to engage the inner curving surfaces of the bent sheet when the stretcher has reached its intended position, the stretcher will be supported in such position by the supporting structure and prevented from further rotation.

The seat 12 is also susceptible of being stamped or die-cut from a sheet of plywood in correct proportion for engaging the inner surface of the supporting structure 10 when the same is bowed and the seat is disposed in its useful position. The cores and wings of the studs 36 and 37 may be cut in the same operation and the studs finished as round bearings and in the manner above described. The studs 36 and 37 are engaged in the openings 23 and 24, respectively, when the stretcher is being assembled to the side portions 15 and 16 of the supporting structure. After the side portions 15 and 16 have been pressed together against the side edges of the seat the seat is rotated to a horizontal position. By further depressing the rear portion of the seat, the material of the supporting structure 10 is flexed sufficiently to permit the seat to descend into contact with the upper edge 26 of the stretcher, as best illustrated in Fig. 2. The seat is locked below the horizontal by the curved portion of the supporting structure 10 and cannot be displaced upwardly without the exertion of considerable force from underneath. The edges of the stretcher and seat engage the interior surface of

the bowed supporting structure and maintain its curved form and the wings on the studs hold the side portions of the supporting structure from spreading away from the stretcher and seat with the result that the three pieces are firmly assembled as a rigid construction.

The invention is admirably suited for the manufacture of chairs and other like pieces of furniture made wholly or partly of plywood. It is apparent that when the stretcher and seat member are detached from the supporting structure, all the pieces may be laid flat for storage or convenience in carrying.

This invention is capable of numerous forms and various applications without departing from the essential features herein disclosed. It is therefore intended and desired that the specific description herein be deemed illustrative and not restrictive and that the patent shall cover all patentable novelty herein set forth; reference being had to the following claims rather than to the particular showing herein to indicate the scope of this invention.

What is claimed is:

25. 1. A knock-down chair or the like comprising a sheet of resilient material bowed from its normal condition into the form of an upstanding supporting structure having a curved back and side portions extending forwardly from the back, a seat member pivotally connected adjacent its forward edge to the side portions of said supporting structure, said seat having a configuration for engaging the curved back, a stretcher pivotally connected adjacent its forward edge to the side portions of said supporting structure and having engagement with the side portions of said supporting structure and the underside of said seat member to support said seat member, and means engaging said seat member and said stretcher, respectively, and the side portions of said supporting structure to hold the side portions of said supporting structure from spreading away from said seat member and stretcher.
30. 2. A knock-down chair or the like comprising a sheet or resilient material bowed from its normal condition into the form of an upstanding supporting structure having a curved back and side portions extending forwardly from the back, a seat member pivotally connected adjacent its forward edge to the side portions of said supporting structure, said seat having a configuration for engaging the interior surface of the curved back when the seat is disposed in seating position between the forwardly extending side portions of said supporting structure, a stretcher extending between the side portions of said supporting structure, said stretcher having side edge portions engaging the inner surfaces of the side portions of said supporting structure to support said stretcher and a rear edge engaging the under surface of said seat member to support the rear of said seat member, and means engaging said seat member and said stretcher, respectively, and bearing upon the outer surfaces of the side portions of said supporting structure to hold the side portions of said supporting structure from spreading away from said seat member and stretcher.
35. 3. A knock-down chair or the like comprising a sheet of plywood adapted to be bowed to form an upstanding supporting structure with a rear and forwardly extending side portions, a seat member shaped to fit within and contact with the inner surface of the bowed configuration
